UNITED STATES PATENT OFFICE.

WILLIAM J. BURTON, OF CHICAGO, ILLINOIS, ASSIGNOR OF ONE-HALF
TO JUANITA M. BURLINGHAM, OF CHICAGO, ILLINOIS.

SWITCHBOARD-CORD.

SPECIFICATION forming part of Letters Patent No. 789,652, dated May 9, 1905.

Application filed February 9, 1904. Serial No. 192,822.

To all whom it may concern:

Be it known that I, WILLIAM J. BURTON, a citizen of the United States, residing at Chicago, county of Cook, State of Illinois, have invented a certain new and useful Improvement 5 in Switchboard-Cords; and I declare the following to be a full, clear, and exact description of the invention, such as will enable others skilled in the art to which it pertains to make 10 and use the same, reference being had to the accompanying drawings, which form a part of this specification.

My invention relates in general to electrical connectors, and more particularly to flexible 15 cords—such, for instance, as are used for connecting subscribers at a telephone-switchboard.

It is essential that flexible electrical connectors which are subjected to frequent use in 20 completing circuits should possess the requisite electrical conductivity and at the same time be sufficiently strong and resilient structurally to stand constant bending without breaking or destroying the conductivity. Owing 25 to the lack of resiliency and strength of copper, considerable difficulty has been experienced heretofore in constructing flexible connectors—such, for instance, as switchboard-cords—which will stand constant usage 30 without wearing out or short-circuiting in a comparatively short while, especially when the diameter of the connector is necessarily of limited size. The wear and tear on switchboard-cords is most severe throughout the 35 portion thereof adjacent to the plug, owing to the plug being forced into the switchboard-sockets by pressure applied to the end thereof, which bends the cord and soon produces a permanent curve therein. Each subsequent 40 insertion of the plug renders such curve more acute, eventually either breaking the conductor or destroying the insulation.

The primary object of my invention is to provide a switchboard-cord which will possess 45 sufficient resiliency to immediately return to its normal position with respect to the plug after each insertion of the latter in a socket, so that the cord will not become permanently bent, thereby prolonging the life of the cord

by obviating the breaking or short-circuiting 50 of the conductors therein.

A further object of my invention is to provide a flexible electrical connector which will be simple in construction, inexpensive in manufacture, and durable in use. 55

The embodiment of my invention herein disclosed consists, generally described, in a switchboard-cord comprising one or more spirally-disposed conductors united at its opposite ends to plugs and resilient reinforcements located within the convolutions of the conductors and extending from within the plugs throughout the portions of the cord on which pressure is applied by the operator inserting the plugs in the switchboard-sockets. 60 65

My invention will be more fully described hereinafter with reference to the accompanying drawings, in which the same is illustrated as embodied in a convenient and practical form, and in which— 70

Figure 1 illustrates a plan view, with parts broken away, of a portion of a cord embodying my invention; and Fig. 2, an enlarged detail view of the resilient reinforcing-rod.

The same reference characters are used to 75 designate the same parts of the two figures of the drawings.

I have illustrated my improvement as applied to a switchboard-cord constructed as described and claimed in the joint application 80 filed by myself and Charles L. Burlingham on February 16, 1903, Serial No. 143,509. The joint invention covered by said application consists in one or more insulated spirally-wound conductors, each conductor consisting 85 in a wire A of a metal possessing strength and resiliency—such, for instance, as brass, aluminium, or steel—around which a fine copper wire B is wound to impart to the conductor the necessary electrical conductivity. 90 An insulating-covering C is wound around each conductor, which may conveniently consist in silk, around which an outer insulating-covering D is placed to retain the silk insulation in position around each conductor, such 95 outer covering preferably consisting in braided thread.

The conductors are wound together in the

form of a spiral, which is incased in an outer covering E of braided cotton thread and a second covering F, composed of braided linen thread. When the conductor is to be used as a switchboard-cord, its opposite ends are secured within plugs, such as indicated at G, consisting in a casing made of insulating material, within which are the usual conductors G' and G'', insulated from each other, as indicated at g, to the latter of which one of the conductors of the cord is united by a set-screw, while the other conductor of the cord is bent into close contact with the conductor G' of the plug.

15 A number of conductors may be wound in a spiral without increasing the diameter of the cord, and by so arranging the conductors the cord is rendered thoroughly flexible. As each conductor consists in an interior wire possessing structural strength and resiliency and of a surrounding metal comprising high electrical conductivity, a conductor results which possesses the requisite conductivity and at the same time is structurally strong. In order, 25 however, that the repeated pressure applied to the portions of the cord adjacent to the plugs incident to the insertion and removal of the plugs from the switchboard-sockets may not permanently bend the cord, and thereby 30 either break the conductors or destroy their insulation, I have found it expedient to insert within the convolutions of the conductors a resilient rod H, which extends from a point within the plug G throughout the adjacent portion of the cord. Such rod H must possess sufficient resiliency to at once spring back 35 into its normal position upon pressure being removed from the cord. Such rod preferably consists in a spirally-wound wire h, the convolutions of which are in close contact with each other, as clearly shown in Fig. 2. Around the resilient rod h is placed an insulating-covering h' to obviate any danger of such rod producing a short circuit through contact 40 with the conductors should the insulation around the same become worn off.

45 By providing the resilient rod within the cord the plug may be inserted by the operator applying pressure to the end thereof without danger of the cord becoming permanently

bent, as the resilient rod at once springs back into its normal position upon the plug being inserted. The breaking of the conductors or the wearing out of the insulation around the same is therefore prevented and the longevity 55 of the cord greatly increased.

While I have described more or less precisely the details of construction, I do not wish to be understood as limiting myself thereto, as I contemplate changes in form, the 60 proportion of parts, and the substitution of equivalents as circumstances may suggest or render expedient without departing from the spirit of my invention.

Having now fully described my invention, 65 what I claim as new, and desire to secure by Letters Patent, is—

1. A flexible electrical conductor wound in parallel convolutions to form a single continuous spiral, said conductor reinforced by a resilient rod located within said spiral at a predetermined locality. 70

2. The combination with a flexible electric conductor comprising a plurality of insulated conductors wound in parallel convolutions to 75 form a single continuous spiral, of a resilient rod located within said spiral.

3. In a telephone-switchboard cord, the combination with a connecting-plug, of a flexible conductor composed of a strong resilient 80 wire around which is wound a good conducting material, said conductor being wound in parallel convolutions, and a resilient rod surrounded by said convolutions and extending a predetermined distance from a point within 85 said plug.

4. The combination with a flexible electrical connector comprising a plurality of insulated conductors wound in parallel convolutions to 90 form a single continuous spiral, each conductor composed of a strong resilient wire surrounded by a good conducting material, of a resilient rod located within said spiral.

In testimony whereof I sign this specification in the presence of two witnesses.

WILLIAM J. BURTON.
